DRY SHAVER

Cornelus Johannes Franciscus Pacificus Van Den Bosch, Eindhoven, Netherlands, assignor, by mesne assignments,
to North American Philips Company, Inc., New York, N.Y., a corporation of Delaware

Application November 21, 1956, Serial No. 43,875

Term of patent 14 years

(Cl. D22—3)

Fig. 1 is a side perspective view of the dry shaver showing my new design;

Fig. 2 is a top plan view; and

Fig. 3 is a side elevational view thereof disclosing the side opposite to that of Fig. 1.

The characteristic feature of my design resides in the specific ornamentation on the side of the shaver as shown in Fig. 1.

I claim:

The ornamental design for a dry shaver, as shown and described.
